FIRE ALARM SYSTEM

Adelard F. Martel, Burlingame, Calif., assignor, by direct and mesne assignments, of two-thirds to George W. Gates, Burlingame, Calif., and one-third to Arthur H. Eldredge, San Francisco, Calif.

Application September 30, 1936, Serial No. 103,260

3 Claims. (Cl. 179—5)

This invention relates to improvements in fire alarm systems.

Among the objects of the invention is to provide automatic means at a central point for indicating the location of the blaze for which the fire alarm is given.

Another object is to utilize the existing individual telephone circuits in the fire alarm system thus enabling individual fire alarm indication by the addition of a common wire only.

Another object is to disconnect the telephone circuit from the fire alarm system so long as the telephone is in use.

Another object is to render the fire location indicators operative until manually restored by the attendant.

Another object is to sound a simultaneous alarm at the fire stations affected so that the equipment is in readiness when the fire station is informed of the location of the fire from the central fire alarm indicator board.

Another object is to permit simultaneous indication of a plurality of fires should occasion arise.

Another object is to provide a fire alarm switch capable of being operated automatically by a rise in temperature or manually.

Other objects and advantages will appear as this description progresses.

In this specification and the accompanying drawings, the invention is disclosed in its preferred form. It is to be understood, however, that it is not limited to this form because it may be embodied in other forms without departing from the spirit of the invention as defined by the claims following the description.

In the two sheets of drawings:

Fig. 1 is a schematic diagram of the wiring of a fire alarm system constructed in accordance with this invention.

Fig. 2 is a horizontal section of the switch for giving the fire alarm.

Fig. 3 is a vertical section of the same.

Fig. 4 is a detail view in side elevation of the time switch for discontinuing the sounding of the alarm at the fire stations.

In detail the construction illustrated in the drawings, referring more particularly to Fig. 1, comprises the telephone line wires 1 and 2. These wires are duplicated as shown at 1' and 2' for each of the telephone units in the system. The wires 1 and 2 are connected to the receiver 3, the transmitter 4, and the signal bell 5 in the manner conventional in this art. The switch 6 maintains the telephone circuit open so long as the receiver 3 is on the hook 7. The wires 1

and 2 lead from the subscriber to the central exchange and terminate in the contacts 8 and 9 set in a jack in the usual switch board. Connection is made between the individual telephone circuits by plugs such as 10 operated by an automatic dial system or by manual means.

The tap wire 11 leads from a line 2 and has the signal relay 12 and a battery 13 connected in series therein. The end of the wire 11 is grounded at 14. The relay switch 15 is interposed in the wire 11 and is adapted to be opened when the coil 16 is energized.

The tap wire 17 is connected to the line 1 and leads to the ground 18 through the relay switch 19. The switch 19 is also opened when the coil 16 is energized.

Raising the receiver 3 from the hook 7 closes the switch 6. Current then flows from the battery 13, through the signal coil 12, the wire 11, the line 2, the closed switch 6 and over the line 1. The circuit is completed through the wire 17, back to the battery 13 through the grounds 18 and 14. The energized signal relay 12 places the automatic dial exchange apparatus in operative condition to receive the dial signals. In the case of manual exchanges, the relay 12 operates an indicator designating the particular jack connected to the calling subscriber.

The relay coil 16 has one end grounded at 20. Its opposite end is connected by the wire 21 to 30 the contactor 22 adjacent the contact 9 in the jack. When the plug 10 is entered into the jack, the contactor 22 engages the contact 9. Current flows from the central source—not shown—to the line 2, through the contactor 22, the wire 21, the coil 16, and back to the source through the ground at 20. Energizing the coil 16 opens the relay switches 15 and 19 and disconnects the operative telephone circuit from the preliminary signal system above described.

The apparatus thus far described is the conventional central exchange telephone system well known to those skilled in the art. Reference may be had to standard textbooks for description of the detailed network. It is deemed sufficient to describe only the elements of that portion of the system to which the present invention is applied.

The apparatus provided by the present invention consists of the drop relays such as 23 which are individually connected by the wires 24 to the tap wires 11 of each of the multiplicity of telephone circuits. The drop relays 23 are preferably located adjacent the telephone exchange boards so that the individual wires 24 can be rel-

atively short. When the telephone circuit is in use the opening of the relay switches 15 and 19 by the relay coil 16 sequesters the fire alarm apparatus from the telephone circuit. The coils 5 23 are adapted to operate the index means 23x so that the exact address of the subscriber is shown when one of the coils is energized.

Each of the coils 23 is connected to the common line 25 which has the relay coil 26 and the 10 battery 27 interposed therein. The coil 26 is adapted to close the switch 28 which is connected to the battery 29 by the wire 30. The opposite 15 side of the switch is connected by the wire 31 to the audible and visual signals 32 and 33 in proximity to the drop relays 23. The wire 34 completes the circuit from the signals 32, 33 back to the battery 29.

Fire alarm signals in the fire houses 35-35 are connected to the switch 28 by the wire 36. 20 The circuit is completed back to the battery 29 by the wire 37.

The motor 38 is also connected to the switch 28 and the battery 29 by the wires 39 and 40 respectively. The motor 38 is the actuating element of a time switch. It comprises the insulating disk 41 driven at predetermined speed by the motor 38. The bus contact 42 is fixed on the disk 41 and is adapted to close the contacts 43 and 44 at the end of a cycle of movement of the time switch.

The contacts 43 and 44 are interposed in a circuit comprising the wire 45, the relay coil 46, the wire 47, the battery 29, the switch 28, and the wire 48. The relay coil 46 controlled by the contacts 43, 44 is adapted to open the switch 28.

The common line 25 extends to the address of each of the subscribers of the given central exchange. It is connected to each of the individual telephone lines 2 by the wires 48. The fire alarm switches 49 are mounted at points convenient to the subscriber and interposed in the wires 23. The switches 49 are preferably protected by breakable glass—not shown—to prevent their mischievous operation. If desired, the switches 45 may be multiplied and connected in parallel in the line 48 as at 49x so that they may be mounted at a number of strategic points.

The construction of the switch 24 is illustrated in Figs. 2 and 3. It consists of the base 50 of porcelain or similar insulating material having the lever 51 centrally pivoted therein. The lever extends through the slot 52 in the base and terminates in the hook 53. The spring 54 urges the lever 51 toward the operative position. The end 55 of the slot limits the operative travel of the lever 51. The lever is arranged so that it moves into and out of engagement with the contact 57 in its travel toward the stop 56.

The lever 51 is normally restrained against operation by the link 58 of fusible material which has one end engaging the hook 53 while its opposite end is anchored by the pin 59. The link 58 is spaced from the body of the base 50 by the lugs 60 in order to render it more responsive to a temperature rise.

The spring contactor 61 is mounted in the base 50 at 62. It is connected to the contact 57 by the conductor 63. It extends over the lever 51 but is normally spaced therefrom, see Fig. 3. It 70 may be manually forced into operative contact with the lever 51 by the push button 64. This enables a fire alarm to be manually effected if conditions warrant.

A blaze will fuse the link 58 permitting the spring 54 to swing the lever 51 through its opera-

tive position. This momentarily closes the given fire alarm circuit as described.

When the circuit is closed, current flows from the battery 27, through the common line 25, the closed firm alarm switch 49, and over the individual line 2 to the central exchange. Here the current passes through the closed relay switch 15, the wire 24, and energizes the coil 23 to operate the indicator 23x. This gives visual indication of the address of the fire. The current continues through the circuit over the wire 25, energizes the relay coil 26, and flows back to the battery 27.

Energizing the coil 26 closes the switch 28. This closes the circuit including the battery 29, the switch 28, the wire 31, the audible and visual 15 signals 32 and 33, and the wire 34 leading back to the battery 29. This calls the telephone operator's attention to the fire alarm. The operator then calls the fire station nearest the blaze and notifies the firemen of the address indicated at 20 23x.

The closing of the switch 28 also completes a circuit through the wire 36 to fire alarm signals located in the fire houses 35-35 and back to the battery 29 through the wire 37. This gives a 25 preliminary signal to the fireman in advance of the call by the telephone operator.

The closing of the switch 28 also supplies current to the motor 38 through the wires 39 and 40. The operation of the motor 38 drives the disk 41 30 at predetermined speed. When the disk 41 has completed one revolution, the bus contact 42 engages the contacts 43, 44. This closes the circuit from the battery 29 through switch 28, the wires 48, 45, the coil 46, and back to the battery through 35 the wire 47.

Thus energizing the coil 46 opens the switch 28. This discontinues the operation of the signals 32, 33 and the signals in the fire stations 35-35. It also cuts off the supply of current to 40 the motor 38. The motor 38 has sufficient momentum after the current is cut off to rotate the disk 41 enough to move the bus contact 41 from engagement with one of the contacts 43, 44. This opens the circuit of restoring relay coil 46 45 so as to preclude its operation at the commencement of the succeeding cycle of operation.

The indicator 23x is manually returned to inoperative position by the telephone operator by any convenient means. This gives the operator 50 unlimited time to call the fire station and to record the address of the fire.

Having described the invention, what is claimed and desired to be secured by Letters Patent is:

1. In combination with a telephone electrical system having a plurality of subscribers' stations therein, each with a pair of individual telephone wires leading therefrom to a central exchange; a common conductor having a source of current 60 therein and leading to said stations and connected to one of each pair of said individual wires through normally open switches, a plurality of electrically operated indicating means at said exchange; the individual wires which are connected to said common conductor, being separately connected to the opposite end of said conductor through said indicating means; and fire alarm means rendered operative by the flow of current in said common conductor.

2. In combination with a telephone electrical system having a plurality of subscribers' stations therein each with a pair of individual telephone wires leading therefrom to a central exchange; a common conductor connected to one of each pair 70

of said individual wires adjacent said stations through normally open switches; a plurality of electrically operated indicating means at said exchange; the individual wires which are connected 5 to said conductor being separately connected to the opposite end of said common conductor through said indicating means; a source of current and a coil in said common conductor; a fire alarm system having a control relay switch operated by said coil; and means for opening said relay switch after a predetermined period when it is closed by said coil.

10 3. In combination with a telephone electrical system having a plurality of subscribers' stations

therein each with a pair of individual telephone wires leading therefrom to a central exchange; normally open switches at said stations connected to one of each pair of said individual wires; means for closing said switches operated by a 5 rise in temperature; a common conductor connected to the opposite side of each of said switches and leading to said central exchange; and a plurality of electrically operated indicating means at said exchange; the individual wires which 10 are connected to said switches being separately connected to the opposite end of said conductor through said indicating means.
